DRAFT CONTROL AND FLY ASH SEPARATOR

Charles Bird, Dayton, Ohio

Application March 4, 1940, Serial No. 322,053

2 Claims. (Cl. 126—280)

This invention relates to a draft control and fly ash separator for furnaces and is designed more particularly for use with a stoker fed domestic furnace. A stoker fed furnace is usually provided with means, such as a motor driven fan, for producing a forced draft through the fire bed while the fuel is being fed thereto. The forced draft is discontinued when the feeding of the fuel is interrupted, the fan motor being stopped when the stoker is stopped or shortly thereafter. During the intervals between fuel feeding operations it is desirable not only that the forced draft be discontinued but that the natural draft be interrupted. Various devices have been provided for automatically interrupting the natural draft when the forced draft is discontinued but these devices have been more or less unsatisfactory in their operation and effect, and, inasmuch as the most of them at least required a damper controlled opening in the smoke pipe, the opening of the damper permitting loose fly ash to escape from the smoke pipe into the furnace room, from which it would find its way into the living rooms and other parts of the house.

One object of the invention is to provide a draft control which will operate automatically without the use of moving parts to effect practically complete interruption of the natural draft when the forced draft is discontinued.

A further object of the invention is to provide a draft control of such a character that it will prevent the escape of loose fly ash into the furnace room at all times.

To this end it is a further object of the invention to provide means for separating at least a substantial part of the fly ash from the products of combustion passing through the smoke pipe and deposit the same at a given point exteriorly of the smoke pipe.

Other objects of the invention may appear as the device is described in detail.

In the accompanying drawing Fig. 1 is a longitudinal sectional view taken vertically of a draft control embodying my invention; and Fig. 2 is a transverse section taken on the line 2—2 of Fig. 1, looking in the direction of the arrows.

In the drawing I have, for the purpose of illustration, shown the preferred form of my draft control and fly ash separator but it will be understood that the apparatus may take various forms without departing from the spirit of the invention.

As illustrated, the apparatus comprises a casing 5 which is here shown as rectangular in shape

but may be of any suitable form. At its opposite ends the casing is provided with an inlet 6 and an outlet 7, the inlet and outlet being preferably in the form of nipples mounted in the walls of the casing and adapted for connection with the respective parts of the smoke pipe 8, the inlet nipple 6 being of course connected with that portion of the smoke pipe which leads from the furnace and the outlet nipple 7 being connected with that portion of the smoke pipe which leads to the stack. Mounted in the casing between the inlet and the outlet is a stationary baffle 9 which is arranged between the inlet and the outlet, which are preferably in alignment one with the other, and is of such an area that it will extend across the inlet and beyond all sides of the latter, but the area of the baffle is less than the cross sectional area of the casing and it is so mounted that its edges are spaced from the walls of the casing on all four sides of the baffle. The baffle may take any suitable form and is preferably mounted in an upright or substantially vertical position. In the form shown, it is rectangular in shape and comprises a vertical lower portion 10 and a forwardly inclined upper portion 11, the lower portion 10 being provided at its lower edge with a rearwardly extending horizontal flange 12. In the arrangement shown, the baffle is supported on the side walls 30 of the casing by transverse straps or bars 13 which are riveted or otherwise rigidly secured to the walls of the casing. The casing is provided in its bottom wall, directly below the baffle, with an air inlet which preferably is in the form of a pipe 14 extending through the bottom wall and downwardly a substantial distance below the casing, usually to a point near the floor of the furnace room, this pipe being of a cross sectional area approximating equal to the cross sectional area of the smoke pipe. Mounted in the air inlet pipe 14 is a normally stationary but adjustable damper 15 which is here shown as an ordinary butterfly damper.

When a forced draft is being passed through the fire bed the products of combustion enter the casing through the inlet 6, passing about the edges of the baffle to the outlet 7 and thence to the stack. The arrangement of the baffle is preferably such that the major portion of the products of combustion passes about the upper and side edges of the baffle and, in the present arrangement, the inclined upper portion of the baffle and the flange 12 tend to divert the gaseous products of combustion upwardly so that only a relatively small portion of the same pass beneath

the lower edge of the baffle. The quantity of the products of combustion which pass below the lower edge of the baffle is not sufficient to draw any large amount of air through the pipe 14 and so far as the operation of the device is concerned it is immaterial whether or not air enters the casing through that pipe, during the operation of the forced draft. However, more or less air will be drawn through the pipe 14 and the arrangement of the baffle is such that the cool air which thus enters the casing will pass at least partly across the back of the baffle and will tend to cool the latter and thereby reduce the injurious effect of the products of combustion on the baffle. Further than this the air will merely serve to more completely fill the outlet portion of the smoke pipe. When the forced draft is interrupted the natural draft in the stack will draw air through the air inlet pipe 14, casing 5 and smoke pipe 8 to the stack, in such quantities as are required by the natural draft. As a result the flow of air or products of combustion from the furnace to the casing 5 is practically interrupted, thus almost entirely if not entirely eliminating draft through the fire bed. The damper 15 is adjusted in accordance with the requirements of the furnace and stack of each installation and, after having been adjusted, remains stationary during the operation of the apparatus.

As the products of combustion enter the casing 5 during the forced draft period they impinge against the baffle 9 and a substantial amount of the fly ash or other solids are separated from the gases and fall by gravity through the lower portion of the casing to the air inlet pipe 14, which then constitutes a discharge conduit for the separated matter. The separated matter as here shown is rather coarse but usually this matter consists mostly if not entirely of fly ash which is of a very fine powdered nature. The solids may be discharged from the pipe 14 onto the floor of the furnace room or into a receptacle 16 placed beneath the pipe, but in either case no loose ash will be permitted to escape into the atmosphere of the furnace room. Unless the discharged ash is permitted to pile up very close to the lower end of the pipe 14 the flow of air through that pipe, when the forced draft has been discontinued, will not carry any part of the ash into the pipe, but should it do so this ash will merely pass out through the stack and no harm will be done.

It will be apparent therefore that I have provided in the present apparatus a draft control which automatically effects substantially complete interruption of the natural draft through the fire bed during the intervals between fuel feeding operations, when the forced draft has been discontinued, and means for preventing the escape of loose fly ash from the draft control apparatus into the furnace room. The construction is very simple but is highly efficient in its operation and can be easily installed in the smoke pipe of the furnace. Preferably the overall length of

the apparatus, including the inlet and outlet nipples 6 and 7, would be equal to the standard length of a section of smoke pipe so that this apparatus could be substituted for a removed section of smoke pipe.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent is:

1. A draft control and ash separator for a furnace of the type having intermittently operating means for creating a forced draft through the fire bed and having a smoke pipe leading to a stack, comprising a casing having an inlet and an outlet on opposite sides thereof adapted to be connected respectively with the furnace and the stack, a stationary baffle mounted in said casing between said inlet and said outlet and in line with and spaced from said outlet, said baffle extending transversely beyond said inlet in all directions and having its several edges spaced from the adjacent walls of said casing to intercept the solid products of combustion while permitting a substantially unrestricted flow of gaseous products of combustion about said spaced edges to said outlet under forced draft, and a constantly open passageway communicating with the lower portion of said casing through which the intercepted solids are discharged and so arranged that upon the discontinuance of the forced draft the natural draft in the stack will draw air through said passageway and substantially eliminate draft through said fire bed.

2. A draft control and ash separator for a furnace of the type having intermittently operating means for creating a forced draft through the fire bed and having a smoke pipe leading to a stack, comprising a casing having an inlet and an outlet on opposite sides thereof, substantially in line one with the other and adapted to be connected respectively with the furnace and the stack, a stationary baffle mounted in said casing between and in spaced relation to said inlet and said outlet and having its upper portion inclined upwardly toward the outlet wall of said casing, said baffle extending transversely beyond all edges of said inlet and having its several edges spaced from the adjacent walls of said casing to intercept solid products of combustion while permitting a substantially unrestricted flow of gaseous products of combustion about said edges to said outlet under forced draft, and a constantly open conduit communicating with said casing below said baffle and extending downwardly therefrom to receive the intercepted solids and so arranged that upon discontinuance of the forced draft the natural draft of the stack will draw air through said passageway and substantially eliminate all draft from the fire bowl.

CHARLES BIRD.
